UNITED STATES PATENT OFFICE

DAVID ADAM CHRISTIAN, OF LONDON, ENGLAND, ASSIGNOR TO SIEMENS BROTHERS & COMPANY LIMITED, OF LONDON, ENGLAND

TELEPHONE SYSTEM

Application filed May 22, 1930, Serial No. 454,712, and in Great Britain May 31, 1929.

The present invention relates to automatic telephone systems and more particularly to arrangements for setting up connections and exchange interconnections in multi-exchange areas. It is particularly applicable to the requirements of rural telephone areas where exchanges may be unattended and cheapness is desirable, but it may also be used in connection with single exchanges.

10 The main feature of this invention is that an exchange apparatus termed an operator circuit, which is available to a number of connecting circuits, exercises a watching function when a connection is being set up and 15 exercises certain other functions in respect of all but the most ordinary calls. For instance, the connecting circuit switches may deal with calls between ordinary subscribers but as regards calls to party lines the operator circuit 20 receives impulses to select the appropriate ringing circuit. Thus, the operator circuit receives at least as many dialled impulses as are required to determine the nature of the call and when it is obvious that no further 25 control by the operator circuit of operations at the exchange is required, it may be arranged that no further digits are recorded or digits may be recorded without the operator circuit exercising any control. The operator 30 circuit may however remain in connection with the connecting circuit for the purpose of supervision (which may include call metering) until the called subscriber replies or if he is engaged, the connection is dropped.

35 The arrangements of the invention permit of several modifications to fit in with the layout of the area and the numbering scheme employed, but in general, impulses dialled by a subscriber are received at an exchange 40 by the selector of the connecting circuit and in the operator circuit, the latter generally recording only as many digits as are required to determine the nature of the call. The impulses may take effect directly on the selector of the connecting circuit or may be repeated by the operator circuit.

45 As regards incoming junctions these may each terminate directly in a connecting circuit with which an operator circuit may be 50 associated, an operator circuit being avail-

able to a number of incoming junctions, and it may be provided that a junction is only marked free at its outgoing end when it has an operator circuit associated with its incoming end, one or more junctions from an exchange being pre-assigned by having an operator circuit associated with them. In the case of incoming junctions the association of an operator circuit with a junction may be 55 made by simple means associated with the junction and the searching and testing functions normally provided in the operator circuit for connecting with a free connecting circuit are not called into use on incoming junction calls, a separate path of entry being 60 employed. The operator circuit performs the watching function previously referred to.

65 In an area comprising a parent exchange and satellite exchanges the operator circuits at these exchanges would exercise a discrimination between local and junction calls. The connecting circuit at the satellite exchange may have two selectors connected to it, one giving access to local subscribers and one to junctions to the parent exchange, both of 70 which are taken into use and a junction to the parent exchange is seized when a call is originated. The operator circuit may be arranged then to release the selector that is not required. The operator circuit records at 75 least sufficient digits to determine the nature of the call and may in the case of a local call cause the absorption of digits not required in setting up the local connection. Alternatively, the selector giving access to the 80 local lines may absorb any unnecessary digits.

85 In a modification the operator circuit when taken into use may cause the selecting switch of the connecting circuit to select a free junction to the parent exchange and take into use apparatus connected to the incoming end of the junction. Impulses would then be received in the operator circuit at the satellite exchange and also at the parent exchange 90 and the operator circuit will cease to record impulses as soon as it is determined that it is a junction call. If the call is determined to be one for a local subscriber the operator circuit will release the selecting switch and 95 100

the junction and allow the selector to be reset by the remaining dialled digits.

Where tandem satellite exchanges exist a junction from the first or sub-satellite to the second or parent satellite exchange would first be taken into use and then a junction from the parent satellite exchange to the main exchange and then a dialling signal may be given. The digits would be recorded in both the sub-satellite and parent satellite exchanges in the operator circuits which may cease to exercise control as soon as it is determined that the call is for the main exchange. If the call is for the parent satellite exchange the junction to the main exchange would be released.

The operator circuit comprises apparatus for performing functions usually performed by a connector thereby simplifying the connecting circuit. In general the operator circuit connects itself to a free connecting circuit, a number of interconnections between the two circuits being provided over which the operator functions are exercised. The operator circuit contains digit switches or like devices for recording digits and may be provided with means for repeating them over the connecting circuit, the setting of the digit switches determining what functions are to be exercised.

The functions which may be performed by an operator circuit besides the recording of digits include the testing of selector outlets, search over the lines of a P. B. X. group, the application of ringing current when required, the selection and connection of an appropriate ringing circuit in the case of party line calls, metering or suppression of metering and connection of tone signals. It may also deal with permanent loop conditions and effect the disconnection of a line from the exchange apparatus and the freeing of the exchange apparatus under such conditions.

As regards the connecting circuit this may be of any known type and provides means for connecting an incoming line with an outgoing line and simulates a cord circuit in a manual system. The type of circuit contemplated is one having a selecting switch for the selection of an outgoing line and in which as regards incoming lines the connecting circuit is available in common to a number of subscribers' lines over a searching switch such as a call finder. In the case of incoming junctions a direct connection to a connecting circuit may be employed. The circuit is provided with a feeding bridge and means for receiving and repeating impulses and supervisory signals.

For the better understanding of the invention reference will now be had to the accompanying drawings which show, by way of example, one method of carrying out the invention. In the example taken a rural area has been assumed comprising a main ex-

change of the usual type employing serially related two-motion selecting switches with junctions to parent exchanges which in turn may have sub-satellite exchanges connected to them by means of junctions. Each sub-satellite is directly connected only to its parent. The circuits shown are suitable for use at either a parent or a sub-satellite exchange, each exchange serving up to 100 lines. A four-figure numbering scheme is employed, the "thousands" digit denoting a particular exchange, and if it is a parent exchange, the digit is also used for its sub-satellites if it has any. As regards the parent and sub-satellite exchanges, discrimination between calls to be completed at a parent or at one of its sub-satellites, takes place according to the "hundreds" digit. Calls from one satellite area, that is, an area comprising a parent exchange and its sub-satellites to another, are completed via the main exchange and one-way junction working is employed.

In the drawings, Figure 1 shows a subscriber's line circuit, Figure 2 a connecting circuit for subscribers' lines and lines incoming at a parent exchange from a sub-satellite exchange. Figures 3 and 3a show an operator circuit. Figure 4 shows the outgoing end of a junction from the main exchange to a parent exchange or from a parent exchange to a sub-satellite, and Figure 5 a connecting circuit terminating the incoming end of such a junction. The line circuit, Figure 1, comprises a combined line and cut-off relay L and the subscriber's meter SM and is connected to bank contacts in two-motion call finders associated with connecting circuits.

The connecting circuit for use on local calls or calls from a sub-satellite exchange and shown in Figure 2 has a two-motion call finder CF and a two-motion connector CS with magnets for their operation, the call finder magnets being designated VM, RM and ZM and the connector magnets VM1, RM1 and ZM1 for the vertical, rotary and release magnets respectively. The connector has also a bank of vertical contacts VC bridged by a wiper which partakes only in the vertical motion of the switch for the control of relay JT and the release of the connector, when required, at the end of discriminating digits. The circuit is provided with a feeding bridge having an impulse relay AA connected to the incoming side and an answering supervisory relay YY connected to the outgoing side. The test relay for the call finder is TC and VA and VY are switching relays.

The operator circuit contains apparatus for performing functions usually performed by the connector, such as testing an outgoing line, the relay for which is designated P, the application and tripping of ringing current, the ring tripping relay being designated TR and other functions which will

be apparent from the detailed description that follows. In the operator circuit is a finder switch which, when an operator circuit is taken into use, searches for and connects it to a free connecting circuit. This switch has seven wipers and banks designated A1 to A7 and associated with it is a similar switch with banks and wipers designated B1 to B7 which is stepped to the position assumed by the former switch to provide interconnections between the operator circuit and the connecting circuit. Switch LS hunts for the level in which the calling line is connected and which is marked in its banks over a level marking wire common to all the lines in a level and simultaneously with its stepping, the call seeker is stepped to the level in which the calling line is connected. DSA and DSB are digit switches which are stepped by dialled impulses to record the digits dialled, or some of them, for the purpose of determining the class of call that is made and the control of the connecting circuit accordingly. The digit switches are connected in turn by a sequence switch SS which also controls circuits for other purposes. The sequence switch has eight wipers and corresponding banks of contacts. For the sake of convenience, however, wipers 2, 4, 5 and 6 are shown dissociated as contacts and are designated by a fraction, the numerator indicating the back contact and the denominator the wiper; the wiper side of the contact is shown as a solid black rectangle, the contact side as an open rectangle. Wipers 1, 3, 7 and 8 are shown in the conventional manner. Stepping switches RC and RD are provided for the selection of a party line ringing code and the intermittent connection of ringing current over the connecting circuit to a called local party line.

A separate entry denoted by the wires E8, E10, E12, E14, E16, E18, E20 and E22 connects the operator circuit over a searching switch to a connecting circuit terminating an incoming junction from the main or parent exchanges. This connecting circuit shown in Figure 5 is of a similar nature to that shown in Figure 2, but is connected directly to an incoming junction instead of being available to a number of junctions. It is provided with a feeding bridge and has a connector for selecting an outgoing line, the connector having a vertical bank of contacts corresponding to the bank VC in Figure 2. A selecting switch ICS connects the circuit to a free operator circuit over the wires E8-E22 and it is arranged that a junction can only be taken into use at the distant exchange when it has an operator circuit connected with it. Only one junction is pre-assigned at a time and when it is taken into use, the searching switches of other connecting circuits search for operator circuits

and when an operator circuit is connected to a connecting circuit, the junction terminated by the connecting circuit is assigned for use. Thus it is always assured that a junction taken into use on calls in a direction from the main exchange to a sub-satellite exchange has an operator circuit connected to its incoming end to receive impulses and to exercise the necessary control.

For the purpose of the following description it will be assumed that the circuits shown are situated at a parent exchange after which consideration will be given to the operations which takes place when the circuits are assumed to be at a sub-satellite exchange.

For the assignment of a free operator circuit to deal with a call, an assigner is employed. The assigner comprises a one-motion switch with driving magnet and controlling relays. A start relay common to a group of lines is provided which when operated starts the switch searching for a free operator circuit. When a line relay is operated, a marking potential is applied to a wire common to all the lines in the level in which the calling line is connected, the several marking wires being connected in multiple to a switch in all the operator circuits accessible to an assigner.

An assigner of the kind which is suitable for use with the present invention is shown and described in British Patent 332,904.

When a local subscriber originates a call, the line relay L in the line circuit operates and starts an assigner searching for a free operator circuit. The connecting circuit finder in the assigned operator circuit then searches for a free connecting circuit of the kind shown in Figure 2 and when found search for the marked level is made by switch LS. Simultaneously with the search for the marked level, the call finder CF is stepped until the marked level being reached search over the level for the calling line takes place and when found it is extended to the operator circuit where dialled impulses are received by relay A. When the line has been found, an impulse is automatically transmitted from the operator circuit to the connector to step it to level 1 over which it searches automatically for a free junction to the main exchange whence a dialling signal is transmitted. The first or "thousands" digit is repeated by relay A to digit switch DSA and over the connector to the main exchange. If the call is not be completed over the main exchange, but is for a local subscriber or a subscriber on a sub-satellite exchange, a cross connection to the bank contact of switch DSA releases the test relay P and effects the operation of the connector release magnet. Switch DSA homes. The second digit is received by switch DSA and steps the connector in accordance with the number of im-

pulses received. This digit then determines whether the call is to be completed locally or at a sub-satellite exchange. If the call is a local one, the connector is released. The 5 "tens" digit steps the connector to the level in which the subscriber's line is connected and switch DSA is also stepped, and the "units" digit rotates the connector over the level to the contacts connected to the wanted 10 line and at the same time switch DSB is stepped to determine whether the line is an ordinary or party line or a line in a P. B. X. group.

If the wanted subscriber is connected to a 15 sub-satellite of the parent exchange, the "hundreds" digit causes the connector to step to a level containing junctions to the required exchange and to search the level for a free junction. The third and fourth digits 20 are then repeated to the sub-satellite exchange and at the same time are recorded on switches DSA and DSB at the parent exchange. When the called subscriber's line is found, ringing current is applied by the operator circuit of the exchange to which the 25 called line is connected and on his reply, the call is metered by the operator circuit of the originating exchange, the parent exchange in our example.

30 If the "thousands" digit determines that the call is to be completed over switches at the main exchange, either for a subscriber thereat or for one on another parent or a sub-satellite thereof, the connector is not released and the remaining digits are repeated over the junction to the main exchange, the digits being recorded on switches DSA and DSB at the parent exchanges as before.

In order that an operator circuit may be in 40 readiness to receive impulses on calls incoming from the main exchange, an incoming junction is terminated by a connecting circuit of the kind shown in Figure 5 and one such junction has an operator circuit always connected to it as far as may be possible, and this junction only is marked free at its outgoing end. On a call from the main exchange, the first digit is taken up in selecting a junction to the required parent exchange. The second digit is recorded in the operator circuit at the selected parent exchange and is recorded on switch DSA and also steps the connector. This digit being 45 that which discriminates between calls to be completed at the parent exchange and calls to be completed at a sub-satellite, further operation depends on the digit received. In the former case, the connector is released and is re-stepped to select the wanted line, the digits 50 being recorded on switches DSA and DSB as before and the line if found free, is rung from the operator circuit. The operator circuit being taken into use over wires E8—E22, no metering is effected by this circuit, this 60 being done at the originating exchange. In

the latter case the connector is stepped by the "hundreds" digit to a level containing junctions to the sub-satellite and a free junction is seized. The operator circuit at the parent exchange is released, further impulses being repeated directly over the connecting circuit to the sub-satellite exchange. 70

As regards a sub-satellite exchange the circuit operation is similar, the parent exchange taking the place of the main exchange as far as the sub-satellite is concerned. On calls incoming from the parent exchange only, two digits will be received at the sub-satellite exchange, suitable strappings on the sequence switch in the operator circuit being provided 80 for the purpose of effecting the required operations.

An outline of the operation of the system having been given consideration will now be given to the more detailed circuit operations. 85

A call originated by a subscriber to the parent exchange will first be considered. When the subscriber lifts his receiver, relay L operates over its winding (I), the calling loop, and battery over contact t_3 . Due to the energization of winding (I) alone, contacts t_1 and t_2 only are operated. Contact t_1 closes a circuit for starting the assigner (not shown) in search of a free operator circuit and contact t_2 connects battery over winding (II) of relay L to the test wire in the call finder multiple. When a free operator circuit denoted by battery over wiper LS3 is found, relay S therein operates and the assigner is stopped. 95

Relay S on operation closes at contact s_2 the testing circuit of relay T. If the connecting circuit finder is in contact with a free connecting circuit, relay T operates. If the connecting circuit is busy, the circuit over wiper A3 will either be open or the wiper will be at substantially earth potential. Relay GMA thereupon operates over back contact t_1 and then to earth either over winding (II) of relay T and contact s_2 or over winding (I) of relay T to the busy earth on wiper A3. Contact gma_1 closes the circuit of magnet DFA and the magnet interacts with relay GMA to step wipers A1—A7 until a free connecting circuit is found, the circuit of relay GMA being opened when magnet DFA operates, by contact dfa_1 . Relay T operates over wiper A3 and vertical off-normal contact on_2 of the call finder of a free connecting circuit, vertical off-normal contact no_3 of the connector of the connecting circuit relay TT to battery and cuts the circuit of relay GMA at contact t_1 stopping further stepping. Relay TT operates in series with winding (I) of relay T and locks up over contact tt_1 . Contact t_1 short circuits winding (II) of relay T and connects earth over contacts s_2 and low resistance winding I to wiper A3 to mark the connecting circuit engaged in the banks of other connecting cir- 100 110 115 120 125 130

cuit finders on the same multiple. Contact t_2 closes a circuit for relay GMB in series with relay TA and relay GMB operating, closes the circuit of magnet DFB. The magnet and relay GMB interact with one another to step wipers B1—B7 until they occupy a similar position with respect to the banks to wipers A1—A7 denoted by a battery connection over wiper A1, whereupon relay GMB is shunted and a low resistance path provided for relay TA which operates and at contact ta_1 opens the circuit of relay GMB, thereby preventing further stepping of the switch. The wipers A1—A7 and B1—B7 now occupy similar positions in their banks and they are both in contact with leads to the same connecting circuit. Contacts ta_3 and ta_4 connect retard coil RC and impulse relay A respectively to wipers A4 and A5 and relay GD operates by means of its winding (I) over normal contact and wiper LS4 and contact ta_5 and td_3 . Contact gd_2 operates relay Q.

Contact gd_4 closes a circuit over contact y_1 for slow releasing relay X which operates and at contact x_1 operates relay Y.

Relay Y on operation opens the circuit of relay X at contact y_1 but this relay does not release immediately. After a short interval, relay X releases and opens the circuit of relay Y which on release, recloses the circuit of relay X at contact y_1 and another cycle of operations is then gone through by these two relays. Each time relay Y operates, contacts of this relay close and deliver a pulse to whichever magnet circuit of the call finder is prepared at the time, relay Y remaining operated long enough for satisfactory magnet operation, due to the slow releasing property of relay X.

Contact gd_3 prepares a circuit for magnet LS which circuit is closed by contact y at each operation of relay Y, the circuit being from earth over contacts y , m_3 , gd_3 , t_4 , magnet LS to battery. Simultaneously with this closure a circuit is closed as follows: earth over contact y , low resistance series winding (II) of relay GD, back contact m_2 , front contact gd_1 , contact t_3 , wiper A6, contact n_1 of the call seeker, vertical magnet VM to battery. At each operation of relay Y, circuits for operating magnets LS and VM are closed and the two magnets step their respective switches synchronously.

Relay TT on operation prepared the test circuit of the call finder test relay TC at contact tt_2 and the holding circuit of the same relay at contact tt_3 and opened a point in the call finder release magnet circuit, and at contact tt_4 opened a point in the connector release magnet circuit and closed a circuit for relay JT over normal contacts of bank VC and contact tc_7 . Relay JT operates and locks up over contact jt_1 .

When wiper LS2 is stepped on to the con-

tact marked over contacts l_5 and l_1 of the line relay and the start wire common to the sub-group of lines, relay M which is connected to wiper LS2 by contact s_1 operates and locks up over contacts m_1 and gd_4 . The circuit of magnet VM is opened at contact m_2 and the call finder is brought to rest with its wipers opposite the level in which the calling line is connected. The circuit of magnet LS is opened at contact m_3 and at front contact m_2 a circuit is prepared for the rotary magnet RM of the call finder. When the call finder made its first vertical step, contact on_1 closed a point in the circuit of release magnet ZM and contact on_2 opened the testing circuit of relay T. The next impulse transmitted by relay Y takes effect on the magnet RM, the circuit being: earth over contact y , winding (II) of relay GD, front contact m_2 , wiper A7 and bank contact, contacts n_1 , tc_5 , magnet RM to battery and this and subsequent impulses rotate the wipers of the call finder round the level until the calling line is found. This line is indicated by the connection of battery over winding (II) of relay L and contact l_2 to the contact in the test bank of the call finder and when wiper C reaches this contact, a circuit is closed thereover for winding (I) of relay TC which operates and at contact tc_1 closes a holding circuit for itself by means of its winding (II). Contact tc_4 connects earth to the test wiper C to mark the line engaged and winding (II) of relay L now being fully energized, contacts l_3 , l_4 and l_5 are operated, the two former disconnecting relay L from the line and the latter opening the start circuit of the assigner. Contact tc_5 opens the circuit of magnet RM and contacts tc_2 and tc_3 connect the calling line over wipers A and B of the call finder and wipers A4 and A5 of the connecting circuit finder to retard coil RC and impulse relay A in the operator circuit. Contact tc_6 opens a point in the circuit of the release magnet ZM to guard against subsequent release of relay TT. Relay A in the operator circuit operates and at contact a_2 operates relay V.

The circuit of the call finder rotary magnet now being open relay GD releases, but before this takes place, contact v_1 connects earth to relay T to hold it on release of relay S.

By the closure of contact v_5 relay DS operates in a circuit including armature contact ss of sequence switch magnet SS, wiper SS7 and normal contact. Contact ds_1 operates magnet SS releasing relay DS. Contact ds_1 opens and magnet SS releases stepping the switch to its first contacts. Relay DS is now connected over wiper SS8, first bank contact, front contact a_3 , winding (I) of relay D to earth. The resistance of this circuit does not permit relay DS to operate but relay D operating prepares a circuit for

relay DS at contact $d1$ and at contact $d2$ connects earth over contact $gd5$ to release the assigner which in turn releases relay S. On the release of relay GD the circuit of relay Q is opened. Before the armature of this relay which is slow to release falls back, a circuit is completed from earth over contact $\frac{1}{4}$ of the sequence switch, contacts $q1, gd1, t3$, wiper A6, contact nrl of the call finder, 10 vertical magnet VM1 of the connector to battery.

The connector is stepped to its first level, the magnet circuit being opened on the subsequent release of relay Q. The vertical off-15 normal contacts $n01, n02$ and $n03$ are operated and a circuit is closed for the rotary magnet RM1 over contact $n01$, wiper A7, contacts $v3, dr1, y$, and the magnet steps the wipers round the level in search of a free 20 junction to the main exchange, the stepping being effected by the interrupter relay Y. Relay DR is operated over the normal bank contact and wiper DSA6 of digit switch DSA and contact $q1$ when relay Q releases and at 25 contact $dr4$, operates relay G. Relay DR holds over contacts commoned in the bank of wiper DSA6 corresponding to lines in the junction group except the last line.

Contact $dr3$ maintains the cyclic operations of relays X and Y on the release of relay GD and contact $dr2$ closes a circuit including wiper SS3 in position 1 over which magnet DSA steps.

A free junction is denoted by battery potential on the test bank contact in the connector and when such a contact is encountered, relay P operates over sequence switch contacts $\frac{1}{5}, g2$, winding (I) of relay P, wiper B7, relay PP, the test wiper and bank contact to battery.

Relay P locks up over its winding (II) contacts $p4$ and $v8$ and at contact $p5$ operates relay PT over sequence switch contact $\frac{1}{6}$, the latter relay locking up over contact $pt1$. Contact $p1$ connects earth directly to relay PP which then operates, and being of low resistance the junction is marked engaged. Contact $p3$ opens the circuit of relay DR which releases and contact $pt10$ closes a homing circuit for switch DSA over contact $\frac{1}{4}$ and wiper DSA1. Contact $dr4$ releases relay G and contact $dr4$ the interrupter relays X and Y. A signal is now sent forward from battery over contacts $pt5, a1$, wiper SS1 and contact 1, contact $pa3$, wiper B4, contact $vy3$ in the connecting circuit, the b wire of the junction to the main exchange to take into use selecting apparatus thereat.

Dialling signal is now connected at the 60 main exchange and is transmitted over the junction a wire, contacts $vy2$, wiper B3, contacts $pa2, pt8$, condenser, wiper A4, the call finder to the subscriber's line.

The calling subscriber now commences to 65 dial the number of the wanted subscriber, the

impulses being received by relay A. At the commencement of the first impulse, contact $a3$ falls back and completes a circuit over wiper SS8 of the sequence switch for relay DS which causes the magnet SS to step the switch 70 to its second position. In this position the circuit of relay DS is open at contact $d1$, relay D holding during impulsion by means of its second winding in a circuit from earth over contacts $a2, v4$, winding (II) of relay D, contact $dr2$, wiper SS3 in position 2, magnet DSA to battery. Impulses are repeated to magnet DSA over this circuit. At the same time the impulses are repeated at contact $a1$ in a circuit over wiper SS1 in position 2, contact $pa3$, wiper B4 and the junction b wire, to the switch connected to the incoming end of the junction to the main exchange. At the end of the impulse train relay A remains steadily operated and relay D releases closing 80 a circuit over contact $d1$ and wiper SS8 for stepping the sequence switch to position 3 whereupon relay D re-operates over its winding (I).

In the bank of wiper DSA5 the contact corresponding to the "thousands" digit of the parent exchange and its sub-satellites is cross-connected to a common wire connected to the holding circuit of relay P and the further operation of the circuits now depends on whether the call is to be completed within the satellite area or via the main exchange. It will be assumed first of all that the call is for a subscriber connected to the parent exchange. The contact to which wiper DSA5 90 is stepped by the "thousands" digit is accordingly connected to the holding circuit of relay P and when the sequence switch is stepped to its third position, a short circuit across relay P, winding (II) is closed over contacts $\frac{1}{4}, p6$, and wiper DSA5. Relay P releases and releases relay PT. At contact $pt7$ earth is connected over contacts $\frac{1}{5}$ and $t5$, wiper B5, contacts 1 in the vertical bank VC to the battery connected side of relay JT 100 also in parallel therewith to contact $jt5$. Relay JT releases and the release magnet is operated over contact $jt5$ and the above traced circuit, its circuit being maintained by contact zm to ensure complete release of the connector. The connector and the junction to the main exchange are released. A homing circuit for switch DSA is closed over contacts $\frac{1}{4}$ and $pt10$.

The "hundreds" digit is now received by 110 relay A and at the commencement of the first impulse, the sequence switch is stepped to its fourth position. The "hundreds" digit for calls to be completed locally is 2 and relay A will receive two impulses which will be 120 repeated at contact $a2$ to magnet DSA which will step its wipers to their second contacts. At the same time impulses will be repeated at contact $a1$ in the following circuit: earth over contacts $v1, p2, n4, a1$, wiper SS1 in posi- 130

tion 4, contacts $pt3$, $gd1$, $t3$, wiper A6, rotary off-normal contact $nr1$ of the call finder, magnet VM1 to battery and the connector is stepped to its second level. At the end of the impulse train, the sequence switch steps to its fifth position in which a circuit is completed over contacts $\frac{1}{2}$, $pt7$, $t5$ and wiper B5 for release magnet ZM1 and the connector is released. The digit switch DSA remains with its wipers on its second contacts. The "tens" digit is repeated to magnets DSA and VM1 in a similar manner to the "hundreds" digit, the sequence switch moving to position 6 at the commencement of the first impulse and to position 7 at the end of the train of impulses representing the digit. With the stepping from normal of the connector, the vertical off-normal contacts are operated and a circuit is prepared over wiper SS1 in position 7, contacts $pt4$, $dr1$, $v3$, wiper A7, connector vertical off-normal contact $no1$ for the connector rotary magnet RM1; a circuit is also prepared over wiper SS3 for magnet DSB. The "units" digit is repeated to these two magnets and the connector wipers are stepped round to the contacts of the wanted subscriber's line, digit switch DSB being stepped at the same time. If the line is an ordinary line, no connection exists over the wipers of the digit switches and the line is tested by relay P. When the sequence switch moved to position 8 during the receipt of the first impulse, a circuit for relay G was closed at contact $\frac{1}{2}$ to provide a fleeting test. During the slow release of relay G consequent on the stepping of the sequence switch to position 9 at the end of the digit, earth is connected over contacts $\frac{2}{3}$, $g2$, winding (I) of relay P, wiper B7, relay PP, the connector test wiper and test bank contact. If the line is free battery potential is found on the contact and relay P operates and locks up over its winding (II); contact $p1$ connecting earth to wiper B7 to mark the line engaged. Relay PP which is of low resistance operates in this circuit and at contact $pp1$ removes a short circuit from winding (II) of relay VY.

On the closure of contact $p5$ a circuit exists for relay PA over contacts $\frac{1}{2}$, and $pt11$ and this relay operates and locks up over contact $pa1$. Relay G now releases and a ringing circuit is closed over the ringing generator and wire RG, contacts $r3$, $pa3$, wiper B4, contact $vy3$, the called subscriber's line and bell, contact $vy2$, wiper B3, contacts $pa2$, $g3$, $r2$ and winding (I) of relay TR, and the called subscriber is rung. At the same time a ringing signal is transmitted to the calling line over wire RS, contacts $r5$, $pa4$, $g1$, $\frac{1}{2}$ of the sequence switch, the condenser and wiper A4.

When the called subscriber answers relay TR operates round the loop and locks up

over its winding (II), contacts $tr1$ and $v1$. Contact $tr2$ connects earth to wiper B6 to operate relays VY and VA in the connecting circuit and contact $tr3$ opens a point in the testing circuit of the assigner. Relay VA connects the calling line to relay AA which thereupon operates, the battery connection being over retard coil RA and contact $ja1$ to the a wire. Contact $aa1$ closes a locking circuit for relay VA over its winding (I) and contact $aa2$ prepares for the operation of relay MR, the circuit being closed at contact $yy2$ of relay YY which operates round the called loop on the change over of contacts $vy2$ and $vy3$, the battery connection being over retard coil RB. Relay MR operates and connects itself over contact $mr1$, off-normal bank contacts and wiper LS4, contacts $ta5$ and $td3$ to earth, and at contact $mr2$ connects battery over wiper A2 and the metering wiper D of the call finder to operate the subscriber's meter SM. Contact $mr3$ opens the circuit of relay V which on release initiates the release of the operator circuit which takes place as follows: contact $v1$ falling back disconnects the general holding earth and relays T and TA release in succession. Relay TT in the connector also releases and releases relay TC which at contacts $tc2$ and $tc3$ disconnects relay A from the calling line. Relay A releases. Relay TR is released at contact $v1$ and relay P at contact $v8$. Contact $p5$ opening releases relay PA and contact $a3$ relay D. At contact $v5$ a homing circuit for the sequence switch over contact $td5$ and the commoned contacts in the bank of wiper SS7 is closed, relay DS and magnet SS interacting to step the sequence switch to its normal position where a circuit is closed over contact $\frac{1}{2}$, wiper LS1, commoned contacts, self-interrupting contact ls , contacts $t4$, magnet LS to battery. Switch LS homes and the assigner testing circuit is prepared over contacts $v9$ and $tr3$. Relay MR releases. At the back of contact $v1$ a homing circuit is closed over wiper DSA1 and contact dsa for the digit switch DSA and when that switch reaches its normal position, a homing circuit for switch DSB is closed over wiper DSB1 and contact dsb . The operator circuit is now at normal and ready for further use.

In the connecting circuit contact $va1$ connects the holding and engaging earth to the call finder test wiper for the calling line and contact $vy1$ connects the holding and engaging earth over relay PP and the test wiper of the connector for the called line. Contacts $va4$ and $vy5$ open points in the circuits of the release magnets ZM and ZM1 respectively. Relay VY locks up over its winding (I) and contacts $jt2$ and $yy1$.

At the end of the conversation when the calling subscriber clears, relay AA releases, releasing relay VA which at contact $va1$ disconnects the earth connection from the call

finder test wiper. Contact va_4 closes a circuit for the call finder release magnet ZM over contacts on_1 , tc_6 and tt_3 , and the call finder is released, the magnet circuit being opened at contact on_1 when the switch reaches its normal position. Relay YY releases when the called subscriber clears and at contact yy_1 releases relay VY which at contact vy_1 disconnects earth from relay PP and the connector test wiper and at contact vy_5 closes a circuit for magnet ZM1 over contact no_2 and tt_4 . The connector is released, the magnet circuit being opened when the switch reaches normal at contact no_2 . The connecting circuit is again free for further use. Should one of the subscribers fail to clear, an alarm circuit is closed over contacts va_5 and vy_6 and wire PL.

When contacts va_1 and vy_1 open, the circuit over the second windings of the respective line relays L are opened and these relays release and connect their line windings to the lines.

If the called line when tested with the sequence switch in position 9 is found busy, relay P does not operate and on the release of relay G which takes place after a brief interval, a busy signal is transmitted over wire BS, contacts n_5 , pa_4 , g_1 , $\frac{2}{3}$ and wiper A4 and the calling subscriber clears. Relay A thereupon releases and opens the circuit of relay V which on release initiates the release of the operator and connecting circuits and the line relay L.

If the "hundreds" digit denotes that the connection is to be completed at a sub-satellite exchange, the "hundreds" digit of which is 8, relay JT is operated at the end of the digit impulses and search for a free and available junction in level 8 is made by the connector. When the sequence switch moves into position 5, a circuit is closed over wiper DSA3 and its eighth bank contact for relay CO which locks up over contact co_1 and wiper LS4 and at contact co_2 connects earth over contact $\frac{5}{6}$ to wiper DSA4. The eighth contact in the bank of this wiper and other contacts in the bank corresponding to the junction group except the last in the group are commoned and cross-connected to the common point connected to the relay DR and relay DR operates. Meanwhile earth over contacts $\frac{5}{6}$, pt_7 , t_5 , wiper B5 and contacts 8 of the bank VC is connected to relay JT and that relay operates and locks up over contacts jt_1 and tt_4 . Contact dr_3 closes a circuit for starting the cyclical operation of the interrupter relays, contact dr_4 operates relay G to prepare the testing circuit, and contact dr_1 closes a circuit over wiper A7 for rotary magnet RM1 to step the connector round the level in search of a free junction. When a free and available junction is found, relays P and PP operate and relay DR is released and a circuit is closed at contact p_5 for relay

PT which operates and locks up. The "tens" and "units" digits are repeated to switches DSA and DSB respectively and also over the junction over contact a_1 , wiper SS1, contact pt_3 or pt_4 , contact pa_3 , wiper B4 and the outgoing b wire. At the end of the "units" digit, the subscriber is rung at the satellite exchange.

When the subscriber answers, battery is connected to the a wire and the signal is repeated over wiper B3, contacts pa_2 , pt_2 , g_3 and relay TR. Relay TR operates and at contact tr_2 operates relays VA and VY. Relay JT holds over contact vy_4 on release of the operator circuit. Relay YY operates over the junction a wire and if the call originated at a sub-satellite exchange repeats the answering supervisory signal thereto at contact yy_3 .

Contacts of digit switch DSB corresponding to party line subscribers are commoned and are connected over contact pt_13 to relay R for the control of switch RC which receives the additional digit dialled to select a particular subscriber on a party line. When a party line subscriber is called, the operation is as previously described up to the reception of the "units" digit and the testing of the line. When the sequence switch steps to position 9 a circuit is closed over contact $\frac{4}{5}$, wiper DSA2 and one of the wipers DSB2—8 as determined by the cross-connections, the contact corresponding to party lines, contact pt_13 and relay R. Relay R operates and locks up over contacts r_1 and v_5 , and at contact r_4 connects magnet RC to contact 9 in the bank of wiper SS3. Contacts r_2 and r_3 disconnect the ordinary ringing circuit and prepare a code ringing circuit. Contact r_6 prepares a circuit for the interrupter relays. The digit indicating the required subscriber on the party line is now dialled by the calling subscriber and is repeated at contact a_2 to magnet RC. The sequence switch steps to position 10 and remains there while the impulses are being received. There is no circuit over wiper SS1 for the repetition of impulses by contact a_1 . Switch RC is stepped by the received impulses to select the required ringing code as determined by the connection of the contacts in the banks of wipers RC2 and RC3. When switch RC comes to rest at the end of the digit, the sequence switch steps to position 11 whereupon a circuit is closed over contacts $\frac{11}{6}$, r_6 and z_1 for relay X. Relays X, Y, and Z interact to produce intermittent operation and relay Y acts as an interrupter for stepping switch RD over contact pa_5 , commoned contacts and wiper RC4 and magnet RD.

Contacts in the banks of wipers RD2—6 are commoned and connected to relay RR in such a way that relay RR is operated in accordance with the ringing code it is required to transmit. Contacts in the latter part of these banks are likewise commoned and con-

nected to relay RT for the determination of the end of a ringing cycle. The contact in each bank prior to these, is connected to wiper RC2 to distinguish between the codes transmitted over the pair of contacts connected together in the bank of wiper RC3.

When the wiper of switch RD which is earthed over wiper RC3 steps on to a contact connected to relay RR, the relay operates and at contact *rr1* connects a continuous ringing generator over wire RG¹ and contact *r3* to the line, the return being over contacts *r2* and *r2*. By this means a code ring is applied to the called line. When the latter part of the bank is reached by wipers RD2—6, relay RT is operated to provide a circuit for relay TR over contacts *rr2* and *r2*, the called line contacts *r3*, *rr1* and *rt1*. A ringing signal corresponding to the code is transmitted to the calling subscriber over wire CRS, contacts *rr2*, *pa4*, *g1*, *12* and wiper A4.

When the subscriber replies to the call, relay TR operates at the end of a ringing cycle and locks up and operates relays VY and VA in the connecting circuit to switch the connection through. Relays AA and YY operating close a circuit for relay MR and the call is metered and relay V released. The release of the operator circuit then follows. On the release of relay V the circuit of relay R is opened at contact *v5* and the relay releases and by the falling back of contact *r4* closes a homing circuit for magnet RC over wiper RC1. When switch RC reaches its home position a homing circuit is closed for magnet RD over wipers RC4 and RD1. Contact *r6* releases the interrupter relays.

When one party on a party line wishes to call another party on the same line, he removes his receiver, dials a special number comprising two digits and then calls the wanted party by means of a hand generator. The first digit of the special number is that denoting a call to be completed without the use of a junction to the main exchange. The digit is received on switch DSA and at the main exchange, and the connector and digit switch are released at the end of the digit. The second digit steps the connector and switch DSA and is such that at the end of the digit when the sequence switch moves into position 5, a circuit is closed over contacts *co3*, *5*, wiper DSA3 and relay RL. Relay RL operates and connects battery over a high resistance and contacts *rl1*, *mr2*, *ta2*, wiper A2 and wiper D of the call finder to an earthed relay in auxiliary apparatus connected in a party line between the main distributing frame and the line circuit. This relay which locks up depending on a receiver being off at an instrument on the party line, holds relay L in the line circuit by means of its winding (II) and marks the line engaged in the connector multiple and no further as-

signment of an operator circuit is made. Contact *rl2* opens the circuit of relay V and the release of the operator and connecting circuits follows. The calling party then proceeds to call the wanted party by means of his hand generator.

When a call is originated by a subscriber at a sub-satellite exchange, a junction to the parent exchange and a junction from the parent exchange to the main exchange is seized as

When a call is originated by a subscriber at a sub-satellite exchange, a junction to the parent exchange and a junction from the parent exchange to the main exchange is seized as before described.

The line circuits of junctions incoming at a parent exchange from a sub-satellite exchange have a battery connection to the metering wire in place of the meter SM. When the junction from the satellite has been found by the call finder CF, relay JC operates over its winding (I), contacts *rl1*, and *mr2*, wiper A2, wiper D of the call finder to battery connected to the metering wire in the line circuit. Relay JC locks up over its winding (II), contact *jc1*, wiper LS4 and contacts *ta5* and *td3*.

The first digit determines whether the junction to the main exchange is to be retained or dropped. If the call is one for the parent exchange the operations are the same as those described for a local call.

When the called subscriber replies to the call, relay MR in the operator circuit is operated and releases relay V which in turn brings about the release of relays TT and TC in the connecting circuit. When relay TT releases contact *tt2* connects earth over relay JA and wiper D of the call finder and this relay operates to the battery connected to the metering wire in the line circuit. Contact *ja1* changes over so that supervisory signals are repeated to the sub-satellite exchange at contacts *yy3*.

If the call is to the main exchange, the first and second digits are recorded on switch DSA in the operator circuit at the parent exchange as in the case of a locally initiated call. At the end of the second digit, the sequence switch moves into position 5 and relay PT having been operated in position 1 of the sequence switch, a circuit is closed over contacts *5*, *pt6*, *jc2*, wiper B6, windings (II) of relays VY and VA, relay PP having operated when the junction to the main exchange was seized. The incoming junction is now switched through to the main exchange and on the operation of relay AA, earth over contacts *jt4* and *aa2* and wiper B2 operates relay MR which initiates release of the operator circuit. The remaining impulses are received direct on relay AA and are repeated over the junction to the main exchange at contact *aa3*; contact *jt3* being open as relay JT is not released on calls to the main exchange. Relay VY locks up over its winding (I) and contacts *jt2* and *aa1*. When the call is answered relay YY operates and relay JA having operated on the release of relay TT,

the answering supervisory signal is repeated over contacts *yy3* and *ja1* to the sub-satellite exchange. The connecting circuit is released when the calling subscriber clears.

At the sub-satellite exchange, the operations of the operator and connecting circuits thereat are similar to those described for the parent exchange except that the operator circuit remains connected to the connecting circuit on all calls originated at the sub-satellite exchange for the purpose of metering the call. The parent exchange takes the place of the main exchange so far as the sub-satellite exchange is concerned.

When a call is originated, a junction to the parent exchange and a junction from the parent to the main exchange are seized and if the call is not to be completed over the latter junction, the latter junction is dropped on completion of the first dialled digit. The second digit then determines whether the call is to be completed via the parent exchange or within the sub-satellite itself and in the former case, the operations are the same as those described for the parent exchange operator circuit on calls to the main exchange. In the latter case the digit being assumed to be 8 when the sequence switch steps to position 5, a circuit is closed over wiper DSA3 and its eighth bank contact for relay CO which locks up over contact *co1* and wiper LS4, and at contact *co2* connects earth over contact $\frac{1}{2}$ to wiper DSA4. The eighth contact in the bank of this wiper is cross-connected to the common point connected to the holding circuit of relay P and relays P and PT are released. Contact *pt7* falling back connects earth over contact $\frac{1}{2}$ and wiper B5 to release the connector and the junction to the parent exchange. The remaining digits then take effect on digit switches DSA and DSB and the vertical and rotary magnets of the connector to select the wanted line which is rung in the manner described. If the line is a party line, the code selecting digit is dealt with in the same manner as described for calls at the parent exchange. When the called subscriber answers, the call is metered and the operator circuit is released. The release of the connection is the same as that previously described.

The operation of the various circuits when a call is made in a direction from the main exchange to a sub-satellite exchange, will now be considered. Junctions for calls in this direction are provided with the arrangements shown in Figure 4 at their outgoing ends, and at their incoming ends they terminate in connecting circuits of the kind shown in Figure 5. These connecting circuits have associated with them searching switches such as ICS which search for and connect with a free operator circuit. The arrangement shown is such that only one connecting circuit has a free operator cir-

cuit allotted to it for immediate use and only when an operator circuit is thus allotted is the junction terminated by the connecting circuit marked free for use at its outgoing end. It will, of course, be realized that other arrangements may be provided whereby any other number of junctions may have operator circuits connected to their incoming ends or all the incoming junctions may have operator circuits connected to them, an operator circuit when required for a call received at the exchange from a local or sub-satellite subscriber being detached from a free junction for use on such a call.

The connection of the connecting circuit with an operator circuit is made over wires E8—E22, the searching function being performed by switch ICS in the connecting circuit. The finder switches of which the wipers are designated A1—7 and B1—7 are therefore not used on calls in the direction, main to sub-satellite exchange.

For the purpose of description it will be assumed that no junction is assigned for use. Battery over relay TD and contacts *v7*, *td1* and *s3* (Figure 3) is connected to wire E22 of a free operator circuit and earth is connected by a contact *gp* of a group control relay over contacts *ab5*, *tb5* and high resistance winding (I) of relay TB.

If switch ICS is not standing with its wipers in contact with a free operator circuit, the bank contact connected to wire E22 will be at substantially earth potential, contact *v7* being open and a resistance being connected in series with relay TD or it will be disconnected.

Relay GM therefore operates in a circuit over armature contact *dm* of magnet DM of switch ICS, contact *tb1*, winding (I) of relay TB, contacts *tb5*, *ab5*, *gp* to earth. Relay GM which is of high resistance operates, but relay TB does not and at contact *gm1* the circuit of magnet DM is closed. The magnet operates and by interaction with relay GM, the switch is stepped until a free operator circuit is found. Relay GM is now shunted by the low resistance battery connection and relay TB operates over both its windings and opens the circuit of relay GM at contact *tb1* stopping further drive by magnet DM.

At the front of contact *tb1* earth is connected over low resistance winding (II) of relay TB to mark the operator circuit engaged and relay TD therein operates. Contact *tb3* connects battery over a retard coil and contact *ab1* to operate the group control relay which at contact *gp* disconnects earth over contacts *ab5* and *tb5* and windings (II) of relays TB in other connecting circuits to prevent search by their searching switches. Contact *tb7* opens a point in a circuit for release magnet ZMA of the connector CCS. Battery is now connected over retard coil RC

(Figure 3) contacts $jc3$, $td4$, wire $E20$, contacts $tb2$ and $vz1$, the junction a wire, contact $tn2$ and relay TS at the outgoing end of the junction. Relay TS operates and at contact $ts1$ connects battery over relay TN to the test bank contact of the junction in the bank of the selecting switch (selector at main exchange or connector at parent exchange). At contact $td1$ the short circuit about the resistance in the test-in circuit over wire $E22$ is removed in order to reduce the potential on the test bank contact of switch ICS .

When the marked junction is taken into use, relay AB operates and at contact $ab1$ releases the group control relay so that earth is again connected at contact gp to allow relays GM in the other connecting circuits to operate. The searching switches step off in search of free operator circuits and one being found, a further junction is marked free and available for use.

As before the case of the operation of the circuits shown in Figures 3, 3a, and 5 when assumed to be at a parent exchange will first be considered. Figure 4 then shows the outgoing end of a junction from the main to the parent exchange.

When a call to be completed over the parent exchange is made, the first digit effects the search at the main exchange for a free junction to the parent, a free junction having an operator circuit connected to its incoming end for immediate use, being denoted by battery potential over relay TN and contact $ts1$ on the test bank contact. When the junction is found relay TN operates and locks up over contact $tn1$ and at contact $tn2$ disconnects relay TS and connects the a wire through to the operator circuit at the parent exchange. Relay AB at the parent exchange operates over the junction b wire to a battery connection in the main exchange. Contact $ab1$ changing over releases the group control relay for the assignment of another junction and at its front contact connects battery over wire $E18$, and contact $td2$ to relay A in the operator circuit. Relay A operates followed by relay V and the sequence switch steps to position 1. At the parent exchange contacts 3 and 4 in the bank of wiper $SS7$ are connected to the commoned contacts (number 5 onwards) and with the switch in position 1 relay DS operates over wiper $SS7$ and contact $td5$, and the switch steps to position 3. Whilst in position 1 relay DR operates over wiper $DSA6$ and at contact $dr3$, operates relay X to start the interaction of relays X and Y for interrupter purposes. Magnet DSA is now operated over wiper $SS3$, contact $dr2$ and interrupter contact y , and when it leaves its normal position, relay DR is released and switch DSA homes, the circuit being over contact dsa , wiper $DSA1$, contacts $pt10$ and $\frac{1}{2}$.

When relay AB operated a circuit was

closed at contact $ab2$ over vertical off-normal contact $nn1$ of the connector CCS for winding (I) of relay C which operated and at contact $c1$ prepared the circuit of the vertical magnet VMA . The "hundreds" digit is now dialled by the calling subscriber and takes effect on relay AB . Contact $ab1$ repeats the impulses to relay A (Figure 3) and contact $ab2$ repeats them to magnet VMA . During impulsive relay C is held by means of its winding (II). The connector is stepped in accordance with the impulses received and on its first step the vertical off-normal contacts $nn1$ and $nn2$ are operated. Contact $nn1$ opens preventing re-operation of relay C at the end of the digit and contact $nn2$ closes a point in the circuit of the release magnet ZMA . In the operator circuit switch DSA is stepped by the intermittent closure of the circuit of magnet DSA at contact $a2$. At the end of the digit, the sequence switch moves to position 5.

Further operation now depends on the exchange to which the wanted subscriber is connected as represented by the digit just received. If the call is for a subscriber on the parent exchange, denoted by the "hundreds" digit 2, earth over contacts $\frac{1}{2}$, $pt7$, $td8$, wire $E8$, rotary off-normal contact nr of the connector, contact 2 in the vertical bank and contact $vn2$ is connected to release magnet ZMA and the connector is released. The "tens" digit impulses are again repeated to magnets VMA and DSA and the switches are stepped as before, the sequence switch moving to position 7 at the end of the train. The first impulse of the "units" train steps the sequence switch to position 8 and the impulses are repeated by contact $a1$ over wiper $SS1$ in position 8, contacts $pt4$, $dr1$, $v3$, wire $E16$, contact $tb4$, and magnet RMA and the connector wipers are rotated to the contacts of the wanted line. Relay G operates and at the end of the digit the sequence switch steps to position 9. The line is now tested by relay P and if found free, ringing current is applied over wires $E12$ and $E14$. Relay TR operates when the called subscriber replies and at contact $tr4$ connects earth over contact $pt7$, wire $E8$, contact nr to winding (I) of relay VZ . Relay VZ operates and at contact $vz1$, connects relay AN to the incoming a wire, at contacts $vz2$ and $vz3$ the connector wipers are disconnected from the operator circuit and connected to the feeding bridge and relay AY operates round the called loop and closes a locking circuit for relay VZ over its winding (II) and contacts $vz7$, $tr2$ and $ay2$. Contact $vz4$ connects earth to the test wiper to mark the called line engaged and contact $vz5$ opens a point in the release magnet circuit against the release of relay TB which is effected at contact $vz6$. At contact $ay1$ relay AY connects itself directly to the outgoing a wire and

at contact ay_3 connects battery over contact ab_4 and relay AN to the incoming a wire to give a supervisory signal at the main exchange. The release of relay TB opens the circuit over wire E18 for relay A at contact tb_3 and the operator circuit releases. Current is fed to the calling line over relays AN and AB and to the called line over retard coil AR and relay AY. When the calling subscriber clears, relay AB releases and contact ab_5 prepares the circuit of relays GM and TB for stepping switch ICS and seizing a free operator circuit. When the called subscriber clears, relay AY releases and at contact ay_2 releases relay VZ which thereupon opens the connections over the connector wipers and at contact vz_5 closes a circuit for release magnet ZMA. The connector is released and the circuits are restored to normal.

If the called subscriber's line is engaged when tested, a busy signal is transmitted over wire E20.

If the called subscriber is connected to the sub-satellite exchange, the "hundreds" digit assumed in the example to be 8, would have resulted in the operation of relay TJ as follows:

At the end of this digit, the sequence switch moves into position 5 and earth is connected over contacts $\frac{5}{2}$, pt_7 , td_8 , wire E8, contact nr and contacts 8 in the vertical bank tj_1 to relay TJ. Relay TJ operates and locks up over contacts tj_1 and tb_6 . Relay CO operates over the eighth contact in the bank of wiper DSA3, contacts $\frac{5}{2}$ and co_3 , and locks up over contact co_1 , commoned contacts in the bank of wiper LS4 and contact td_3 . Contact co_2 connects earth over contacts $\frac{5}{2}$ and wiper DSA4 and its eighth bank contact cross-connected to relay DR and relay DR operates and starts the interrupter relays at contact dr_3 . Relay DR is cross-connected to all contacts in the bank of wiper DSA4 corresponding to lines in the junction group except the last line.

Impulses are transmitted over contacts y , dr_1 , vz_3 , and wiper E16, contact tb_4 to the rotary magnet RMA which steps the wipers round the bank in search of a free and available junction to the sub-satellite exchange. Relay G is operated at contact dr_4 to prepare the test circuit over wire E10 so that relay P operates when a free junction is found and operates to relay PT.

Contact p_3 releases relay DR to prevent further stepping by magnet RMA. Contact pt_{12} closing connects earth to wire E8 and relay VZ operates and locks up over its winding (II) and contacts vz_7 , tj_2 and ab_2 . Contact vz_6 releases relay TB and the feeding bridge is connected to the connector wipers. Battery over retard coil AR, contacts ab_3 and vz_3 , and the b wire effect operation of relay AB in the corresponding circuit at

the sub-satellite exchange and the remaining digits are repeated to the sub-satellite exchange over contact ab_3 . The operator circuit is released consequent on the opening of contact tj_3 . The called subscriber is rung from the operator circuit at the sub-satellite exchange and when he replies to the call, the answering supervisory relay in the connecting circuit thereat operates and repeats the signal, operating relay AY which in turn connects battery over relay AN to repeat the signal to the main exchange.

The release of the connection takes place as for a local call.

At the sub-satellite exchange, similar arrangements are provided but as the operator circuit has to deal with only two digits on calls from the parent exchange, contacts 3 and 4 in the bank of wiper SS7 are strapped to contacts 1 and 2 as shown by the dotted line; consequently when the operator circuit is taken into use and relay V operates, the sequence switch is stepped to position 1 in the normal manner and then continues to step due to the operation of relay DS over wiper SS7 and contact td_5 until position 5 is reached. The "tens" digits is received in the operator and connecting circuits and steps the connector vertically, and also steps switch DSA, the sequence switch moving to position 6 at the first impulse and to position 7 at the end of the train. At the end of the "units" digit which steps switch DSB and magnet RMA, the circuit for the latter being over wiper SS1 and contact a_1 , the sequence switch moves to position 9 where test of the calling line is made. The subsequent operations are the same as those described for the circuits at a parent exchange for a call to a locally connected subscriber.

There may be P. B. X. subscribers' connected to a parent or sub-satellite exchange, and to call such a subscriber, the number of the first line in the P. B. X. group is dialled. Contacts in the banks of wipers DSB2-8 corresponding to lines of a P. B. X. group, except the last line of a group, are commoned and connected to relay DR to permit of searching by the connector. When the connector, either CS or CCS, steps onto the first line of a P. B. X. group in accordance with the number dialled, the sequence switch steps to position 9 and the line is tested and if free, relay P operates. If, however, it is busy, relay P does not operate but relay DR does over the commoned contacts in the switch DSB, wiper DSA2 and contact $\frac{9}{4}$ and the interrupter relays are started and impulses are transmitted over contacts dr_1 and vz_3 to the connector rotary magnet, relay G being held by contact dr_4 to connect relay P to the test circuit. Search and seizure of a free line takes place in the manner described for a junction from the parent to a sub-satellite exchange.

Provision is made for offering trunk calls to busy subscribers by a manual operator at the main exchange. When a parent or sub-satellite exchange operator circuit is taken into use over a junction incoming from the direction of the main exchange, a circuit is closed over contacts $td7$, $v10$, $n12$ and $n11$ for winding (I) of relay JC. Relay JC operates and locks up over its windings (II) contacts $jc1$ and $td3$ and at contact $jc3$ connects relay N over contact $td4$, wire E20, contacts $tb2$ and $v21$ to the incoming a wires. When the line of a subscriber wanted for a trunk call is tested and found busy, a busy signal is transmitted in the ordinary manner and the manual operator at the main exchange may then connect battery to the junction a wire and operate relay N. If the subscriber is at a sub-satellite exchange, the battery connection operates relay AN in the connecting circuit at the parent exchange and contact $an1$ connects battery over retard coil AR and back contact $ay1$ to the a wire of the junction to the sub-satellite exchange to operate relay N in the operator circuit thereat. Contacts $n2$ and $n3$ close a talking circuit over wires E20 and E18, contacts $pa2$ and $pa3$ wires E14 and E12 to the wanted line. Relay G is operated from earth over contacts $v1$, $p2$ and $n4$ and the manual operator offers the trunk call and requests both subscribers to clear. When the wanted subscriber has cleared, relay P operates and the connection is completed in the normal manner. The above mentioned talking circuit is disconnected when the called subscriber answers at contacts $v21$ and $v22$.

When an operator circuit is taken into use relay V operates and at contact $v2$ prepares a circuit for one of a pair of delayed alarm relays and contact $v6$ closes a circuit for setting into action a timing device. Earth is periodically connected to wire 10 and on the elapse of a prescribed period after this earth connection, a momentary earth connection is made to wire 11. When earth is connected to wire 10, relay SA operates and locks up over contact $sa1$ and at contact $sa2$ connects relay ZA to wire 11. On the elapse of the prescribed period, earth is connected to wire 11 and if the operator circuit is still in use, denoted by the continued operation of relay V, relay ZA operates and locks up over contact $za1$. Contact $za2$ connects earth over wiper B6 to operate relay VA in the connector circuit (Figure 2) and contact $za3$ releases relay V. When relay V releases, the locking circuits of relays SA and ZA are opened in turn and these relays release. Relay VA connects the calling line to relay AA and the connecting circuit remains held until the calling loop is opened. Contact $va5$ changing over and contact $vy6$ not being operated owing to the short circuit across its winding (I) and relay JT not being ener-

gized, an alarm relay is operated over wire PL. Contact $n1$ in the circuit of relay SA prevents the throw-out of the operator circuit when a manual operator at the main exchange offers a trunk call to a subscriber at 70 a parent of sub-satellite exchange.

What I claim is:

1. In an automatic telephone system, a sub-exchange, a link circuit, a common controlling circuit, means for temporarily associating said circuits, a plurality of trunk lines extending to a main exchange, means controlled by the association of said circuits for operating said link circuit to find an idle one of said trunk lines, a register, means for setting said register in accordance with received impulses and for simultaneously repeating said impulses over said trunk line, and means for releasing said trunk line when the setting of said register determines that the call is for a subscriber in said sub-exchange. 80

2. In an automatic telephone system, a link circuit, a common controlling apparatus, means for temporarily associating said common controlling apparatus with said link circuit, a plurality of trunk lines extending to another exchange, means for operating said link circuit to find an idle one of said trunk lines, a register, means in said common controlling apparatus for setting said register in accordance with received impulses and for simultaneously repeating said impulses over said trunk line, and means for releasing said trunk line when said register is set to a predetermined position. 90

3. In an automatic telephone system, a sub-exchange comprising a link circuit and a common control circuit, means for temporarily associating said circuits, a plurality of trunk lines extending to a main exchange, means controlled by the association of said circuits for operating said link circuit to find an idle one of said trunk lines, a register, means for setting said register in accordance with received impulses and for simultaneously repeating said impulses over said trunk line, a source of ringing current, means for disconnecting said ringing current at the common control circuit when said register determines that the call is for the main exchange, and means for maintaining said link circuit and said common control circuit associated until the called subscriber in the main exchange answers. 105

4. In an automatic telephone system, a sub-satellite exchange and a parent satellite exchange each comprising link circuits and common controlling circuits, means for temporarily associating said common controlling circuits with said link circuits to register received impulses and to control said link circuits, a main exchange, inter-connecting trunk lines between said exchanges, means responsive to the initiation of a call at the sub- 125

satellite exchange for seizing a trunk line to the parent satellite exchange and a trunk line from the parent satellite exchange to the main exchange, and means for repeating the impulses dialled by the sub-satellite subscriber to the parent satellite exchange and main exchange.

5. In an automatic telephone system, a sub-satellite exchange and a parent satellite exchange each comprising link circuits and common controlling circuits, means for temporarily associating said common controlling circuits with said link circuits to register received impulses and to control said link circuits, a main exchange, inter-connecting trunk lines between said exchange, means responsive to the initiation of a call in the sub-satellite exchange for seizing a trunk line to the parent satellite exchange and a trunk line from the parent satellite exchange to the main exchange, means for repeating the impulses dialled by the sub-satellite subscriber to the parent satellite exchange and main exchange, and means for releasing the common controlling circuit used in establishing the connection at the parent satellite exchange when it is determined by the digits dialled that the call is for said main exchange.

6. In an automatic telephone exchange, a plurality of connecting circuits common to a plurality of subscribers, a plurality of controlling circuits common to a larger plurality of connecting circuits, other connecting circuits, incoming trunk lines from another exchange permanently connected to said other connecting circuits, and means for temporarily associating said controlling circuits with said other connecting circuits.

7. In an automatic telephone exchange, a plurality of connecting circuits common to a plurality of subscribers, a plurality of controlling circuits common to a larger plurality of connecting circuits, other connecting circuits, incoming trunk lines from another exchange permanently connected to said other connecting circuits, a switch individual to each of said other connecting circuits and having access to a plurality of said controlling circuits, means for operating one of said switches to connect the associated connecting circuit with an idle one of said controlling circuits, and means responsive to said connection for rendering the associated trunk available at the other exchange.

8. In an automatic telephone exchange, a plurality of connecting circuits common to a plurality of subscribers, a plurality of controlling circuits common to a larger plurality of connecting circuits, other connecting circuits, incoming trunk lines from another exchange permanently connected to said other connecting circuits, a switch individual to each of said other connecting circuits and having access to a plurality of said control-

ling circuits, means for operating one of said switches to connect the associated connecting circuit with an idle one of said controlling circuits, a relay connected to the associated trunk operated responsive to said connection to apply a potential denoting the idle condition of said trunk at the other exchange, and means for disconnecting said relay and for completing a talking circuit when the idle trunk is seized.

9. In an automatic telephone system, a connector switch, a common-control unit temporarily associated with said switch for the control of switching and other operations involved in the setting up of a connection, means in said unit for recording received impulses simultaneously with the setting of said connector, individual, party, and trunk lines accessible to said connector, and means for modifying the controlling functions of said unit in accordance with the class of the line indicated by the setting of said recording means.

10. In an automatic telephone system, a connector switch, a common controlling unit temporarily associated with said switch, a register in said unit, means in said unit controlled by received impulses for simultaneously setting said switch and said register, and means controlled in accordance with the setting of said register for transmitting signalling current through said switch when an ordinary line is called, for transmitting coded signalling current through said switch when a party line is called, and for preventing the transmission of signalling current when a trunk line is called.

11. In an automatic telephone system, a sub-exchange, a connector switch in said exchange for extending connections to a main exchange or to subscribers in said sub-exchange, a common control unit, means responsive to the initiation of a call for temporarily associating said unit with said connector, means in said unit for controlling said connector to find an idle trunk line extending to the main exchange, a register, means in said unit responsive to impulses transmitted by the subscriber initiating said call for operating said register and for repeating the impulses over the selected trunk line, and means for releasing said trunk line when the impulse recorded by said register determine that the wanted subscriber is in said sub-exchange.

In testimony whereof I affix my signature.
DAVID ADAM CHRISTIAN.
